METHOD AND APPARATUS FOR APPLYING
RADIUM-LUMINESCENT MATERIALMarvin R. Saxby, Pleasant Plains, Staten Island,
N. Y., assignor of sixty per cent to George Mur-
ran, New York County, N. Y.

Application June 12, 1941, Serial No. 397,684

27 Claims. (Cl. 101—318)

This invention relates to the application of radium-luminous material to a receiving surface, and with particularity to such application with a minimum of personal contact with the luminous material.

I am aware that machines have heretofore been proposed for applying radium-luminous paint to such devices as clock and watch dials, with the object of avoiding personal contact with the paint material. However, for various reasons which will be pointed out herein, these prior proposals have not been entirely satisfactory. One of the main difficulties encountered in machines of the type under consideration, is the necessity of maintaining the radium-luminous material uniformly distributed in its vehicle or liquid suspension. Because of the very heavy nature of the radium-luminous crystals or particles, they tend to separate out very rapidly. Various means have heretofore been proposed to maintain the crystals uniformly distributed. Thus in one type of machine, the paint is carried in a tubular reservoir which is turned upside down at regular intervals to effect a mixing action on the paint. However, because of the heavy character of the particles, they tend to compact and lodge at the ends of the reservoir. Furthermore, with the prior type of mixing device, it is necessary to charge the reservoir with a considerable quantity of the paint so as not to interrupt the operation of the machine. I have found that this large quantity of charge causes the particles at the lower end of the reservoir to be subjected to considerable pressure by reason of the weight of the supervening column. This weight further tends to compact the crystals. In addition where the charge is applied to the moving reservoir in large quantities, it is very difficult to maintain its consistency or viscosity uniform over an extended period of time. Accordingly, it is a principal object of this invention to provide an improved method and apparatus of supplying radium-luminous paint to the printing or transfer mechanism of an automatic applicator machine whereby the particles are at all times substantially uniformly distributed in the liquid vehicle, and the danger of compacting of the particles is reduced to a minimum.

I have found that with prior machines, the luminous efficiency of the printed characters or indica varies considerably from batch to batch, and after careful investigation I have found that this variation results in great part from the pressure to which the crystals have heretofore been subjected during agitation and transfer to

the printing surface. Furthermore, in prior machines the luminous paint must be ejected or expressed from the mixing reservoir into a mold to form the indicia. Thus in one type of machine, a piston-like plunger is arranged for reciprocation within the reservoir and is operated by a rack and pinion to force the paint out through a nozzle attached to the reservoir. Inasmuch as the luminous efficiency is a function of the pressure to which the crystals are subjected, it is at once apparent that this prior method of forcing or expressing the paint results in a considerable loss in ultimate efficiency as well as a waste of paint which is comparatively expensive.

Accordingly, it is another principal object of this invention to provide a method and apparatus for transferring radium-luminous material from a supply to a receiving surface while subjecting the crystals to a minimum of pressure and with a minimum waste.

In such devices as dials for clocks, watches, aeroplane instruments and the like, it is customary to provide the indicia on the dial in the form of raised characters employing an intermediate molding step. Heretofore, in machines of the type designed to imprint such characters, the material after agitation in the reservoir, is transferred in a liquid or viscous state to a mold wherein are formed the respective solid indicia, and then after hardening the molded indicia are transferred from the mold to the final receiving surface. Therefore, it is another principal object of the invention to provide an improved process and apparatus for directly forming and printing raised characters or indicia of radium-luminous paint.

Another object is to provide a completely automatic machine for printing raised indicia on a continuous web.

Another principal object is to provide a novel method and apparatus for printing and forming raised characters employing a paint-like liquid.

A feature of the invention relates to a novel printing device comprising constantly rotating quill-like members arranged in groups corresponding to the desired indicia or characters to be printed.

Another feature relates to a novel mechanism for loading and stripping a plurality of rotating printing quills. Preferably and in accordance with the invention, the loading and stripping mechanism is adjustable to control the quantity of printing liquid or paint carried by the quills.

A further feature relates to a novel raised-

character printing device comprising a plurality of constantly rotating quills which are movable as a unit in a direction parallel to their axes of rotation, in conjunction with a special stripping shield for sharply delineating the boundary of the printed characters.

A feature of the invention relates to an automatic machine for printing raised characters comprising a bank of rotating printing quills which are movable bodily in a vertical direction, in conjunction with a horizontally movable trough for carrying a limited quantity of the printing medium into loading relation with respect to the quills.

A further feature relates to an automatic machine for printing raised characters comprising a trough-like member for receiving the printing medium, in conjunction with a vane-like distributor coacting with the trough to localize the supply of printing medium with a minimum of pressure thereon.

A further feature relates to an automatic machine for printing raised characters employing a paint-like printing medium, wherein the printing is effected by banks of rotating quills past which the printing surface is moved, and a reservoir containing the paint is moved between the quills and printed surface to load the quills, in conjunction with means for automatically controlling the amount of paint transferred to the quills from the reservoir.

Another feature relates to a novel form of inking carriage and supply reservoir for an automatic printing machine.

A further feature relates to an improved agitating and wiping arrangement for the ink-supply of an automatic printing machine employing a radium-luminescent printing paint and the like.

A still further feature relates to the novel organization, arrangement and relative location of parts which constitute an improved and efficient machine for printing with radium-luminescent paints and the like.

General method of operation

Apart from the novel mechanism which is involved in the machine, it is believed that a clearer understanding of its operation can be had after considering the method of printing which also constitutes an important phase of the invention. For this purpose, reference may be had to Figs. 21 to 27. The paint or other medium which is to form the raised characters is designated by the numeral 1, and may be in the form of a paste or liquid suspension of radium-luminous particles or crystals in a suitable liquid vehicle. Preferably, although not necessarily, the medium 1 is used with a predetermined viscosity. For purposes of simplicity, the medium 1 will be referred to throughout the subsequent description as paint, although not in any sense by way of limitation thereto. The paint is deposited in any suitable manner in a longitudinally extending channeled member 2 forming a trough within which is adapted to reciprocate the pivotally mounted wiper blade or vane 3. Trough 2 has its surface undercut to receive a quantity of the paint which can be localized therein when the vane 3 moves in the direction of the arrow (Fig. 21). Preferably, this undercut is shaped to con-

form to the outline of the particular character or indicia to be printed, thus as shown in Fig. 3 it is in the form of a recess 4 in the shape of the indicia "2." Preferably, the vane 3 is of spring metal such as Phosphor bronze and is slightly inclined with respect to the bottom of trough 2 so as to exert a light wiping action on the paint 1 while lightly and resiliently pressing against the bottom of the trough. Consequently, as the vane moves to the right, it causes the recess 4 to be filled with the paint and the edge of vane 3 strips the excess paint. At each stroke therefore, the level of paint in the recess remains of uniform depth. When the vane 3 reaches the limit of its travel towards the right as indicated by the dotted outline (Fig. 21), it is tilted in the opposite direction as indicated by the dotted outline (Fig. 22), and it then moves to the left, back to its original position. By this light wiping motion of the vane, the recess is always kept uniformly filled and a minimum of paint is required at each loading of the quills. Consequently, it is possible to maintain the particles substantially uniformly distributed throughout the paint in the recess 4. Furthermore, the light wiping action of vane 3 subjects the crystals to a continuous gentle agitation without any substantial pressure which would otherwise reduce the luminous efficiency of the radium-activated crystals. I have found that in order to achieve these effects, it is preferable to make member 2 or at least its surface and also the lower ends of the quills of a special alloy which does not react deleteriously with the radium paint and which does not result in a caking of the paint on the surface. As an example of an alloy that has been found successful for these purposes, may be mentioned "18-8" stainless steel. The alloy must have a hard wearing surface preferably of the order of austenitic steel and which is non-magnetic and polished. As a substitute for the above-noted alloy, Monel and similar hard "stainless" alloys may be used.

Located above the recess 4 and arranged to be raised and lowered as a unit, is a bank of rotatable printing fingers 5, the lower ends of which are concave as shown in the magnified views of Figs. 19 and 20. For purposes of description, these fingers will be referred to herein as "quills." The quills when lowered into the paint 4 are continuously rotating about their individual axes and each quill picks up a definite quantity of paint. I have found that the concavity of the quill end is necessary due to increased surface tension. The quills are then raised out of the paint and each quill carries a certain quantity of paint not only in the concave portion but also on the peripheral portion designated by the numeral 6 (Fig. 19). Before printing, it is necessary to remove this peripheral excess and for this purpose the quills pass upwardly closely through the stripper plate 7. This upward movement of the quills is continued until their lower ends are flush with the under surface of the stripper plate whereby the excess paint on the periphery of each quill is stripped and drops back into the trough 2 (Figs. 22, 23). Instead of moving the quills upwardly to bring their lower end flush with the lower face of stripper plate 7, the latter may be moved downwardly under control of a cam so as to control the amount of paint on each quill which projects below the under surface of the stripper plate. The paint which is left on the quills will therefore be roughly elliptical in vertical section as illustrated in the magnified

view of Fig. 20. It will be understood of course that because of the comparatively heavy weight of the paint, it sags below the quill and the volume of paint picked and retained by each quill will depend not only upon the viscosity of the paint but also on the depth and dimensions of the concavity in the quill end. By properly designing the dimensions and shape of this concavity in correlation with the range of viscosity encountered in the paint, the initial and final quantities of paint on each quill can be accurately controlled. As a further control over the amount of paint that is actually transferred from the quills to the final printing surface, a reciprocating wiper blade 8 may wipe across the loaded ends of the quills to remove the paint which projects below the under surface of the stripper plate 7 as indicated in Fig. 20. By making the plate 7 adjustable with respect to the final upward position of the quills, the amount of paint which sags below the surface of stripper plate 7 can be accurately gauged and consequently the amount that is removed by the wiper blade 8 can likewise be accurately gauged.

When the quills have been properly loaded, they are then lowered, while still rotating, into printing contact with the printing surface or web 9 (Fig. 26). The quills are then raised above the web 9 to provide sufficient clearance to allow the loading trough 2 to enter between the web and the quills whereupon the foregoing cycle of operations is repeated. During this last-mentioned vertical movement of the quills (Fig. 27) a series of pointed fingers 10 are forced upwardly through the web 9 adjacent each margin and these fingers are then bodily moved in the direction of the arrow (Fig. 27) to feed web 9 in readiness for the next printing impression. The above cycle of operations is repeated for each successive impression. It will be understood that the quills are arranged in banks, each bank having a cross-sectional trace or configuration corresponding to the desired character or impression to be printed. In the actual machine to be described, the trough 2 is movable into and out of the space between the quills and the printing web, the timing being such that it is moved beneath the quills only when the latter are in their completely raised position. Likewise, the wiping and agitating movement of vane 3 is executed when the trough 2 is in a position where it is entirely clear of the quills. I have found that with the foregoing method employing the constantly rotating concave-end quills, it is possible to print and form directly on the web 9 raised characters of a relatively sharply defined outline wherein the completed character consists of a series of sharply defined discrete raised dots such as shown in Fig. 28. These dots are sufficiently close together so that in the dark they give the impression of a continuous illuminated indicia. By using dots, the quantity of radium-luminous material that is necessary for the desired luminous area is materially reduced as compared with a correspondingly thick indicia of uniform thickness. The sharpness and luminous efficiency of the individual dots constituting the printed indicia probably is caused by the fact that the only physical engagement between the quills and the printing surface is that which may occur at the comparatively sharp thin edge 11 (Fig. 19) of each quill. Furthermore, in order to deposit the paint on the printing surface or web, it is not necessary to subject the web or the paint to any appreciable pressure from the quills. While I am not entirely

sure as to what causes the paint to be withdrawn from the quill ends on to the printing surface, it is likely that it is due to the fact that the quills are rotating and because of the special alloy of the quill ends there is a greater adhesive force existing between the web and the paint as compared with that normally holding the paint in the quill concavity. Preferably, the quill ends should be made of a special alloy similar to that of the trough 2 so as to exert a minimum adhesive force on the paint and so that once contact is made between the paint in the quill end and the web 9, the surface tension of the paint in the quill concavity is broken and gravity assists in depositing the paint on the web. If desired, the downward movement of the quills can be regulated so that the edges 11 of each quill execute a slight "bite" into the web.

Detailed description of the machine

A machine for carrying out the method above described is shown in detail in Figs. 1 to 20. Referring more particularly to Figs. 1, 2 and 3, the machine comprises a bed plate 100 to which are rigidly fastened five main supporting pillars 101-105. The pillars 101-104 support at their upper ends a platform 106 on which is supported the paint trough 2, and the mixing and inking carriage designated by the general numeral 107 and shown in perspective in Fig. 16. The pillar 105 telescopically supports the sleeve 108 which in turn carries the printing quill and stripper assembly designated generally by the numeral 109.

Mounted at the right-hand rear portion of plate 100 is a suitable power motor 110 which drives, by a belt 111, a pulley 112 fastened to shaft 113. Shaft 113 is provided with suitable bearings in the brackets 114, 115, carried respectively by bed plate 100 and platform 106, and has fastened to its left-hand end a worm 116. Worm 116 meshes with worm-wheel 117 affixed to cam-shaft 118 supported in suitable bearing brackets 119, 120 (Fig. 4). Affixed to shaft 118 are five cams four of which are shown in detail in Figs. 5, 6, 7, 8 respectively. The angular position of the cams on the shaft 118 are as shown in Figs. 5 to 8 so as to provide the required timing between the various operations to be described. Cam 121 controls the movement of the ink agitating and wiping carriage. Cam 122 controls the web piercing fingers 10, while cam 123 controls the feeding movement of the printed web. Cam 124 controls the raising and lowering of the printing quill and stripper assembly 109. Shaft 118 also has fastened to its forward end a bevel gear 125 meshing with another bevel gear 126 which is attached to a stub shaft 127 supported in bearing brackets 128, 129, fastened to plate 100. Shaft 127 carries a cam 130 for controlling the movement of the paint trough into and out of loading engagement with the quills.

Fastened at the opposite ends of platform 106 are guide rails 131, 132 (Figs. 1 and 3), which extend parallel to each other and to the rear edge of platform 106 where they have vertical stops 133 to limit the backward movement of the paint trough 2. Trough 2 consists of a metal casting having a flat bottom and two side walls 134, 135, having flat upper faces to serve as guide rails for the carriage 107 (Fig. 16). In accordance with a feature of the invention, the bottom wall of the trough is of any well-known stainless steel alloy but preferably a non-magnetic alloy of the type known to the trade as "18-8" stainless steel. This

alloy I have found enables the radium paint to be wiped back and forth with a minimum of caking and without danger of contamination or corrosion on the trough surface. However, if desired, the trough may be of ordinary steel and a layer 136 of the above alloy may be fastened in any suitable manner to the bottom and to the interior surfaces of the side walls of the trough. The trough carries at opposite ends downward extending flanges 137, 138, in which are rotatably mounted rollers 139, 140, 141 and 142, which ride upon the guide rails 131, 132. Each of the rollers has a shoulder bearing against the side walls of the rail to guide the trough thereon.

The trough tends to assume a position forwardly of the platform 106 limited by a pair of stops 144, 145 attached to the rails, this forward position being controlled by tension springs 146, 147, each having an end fastened to the trough and an opposite end fastened to corresponding brackets 148, 149, attached to platform 106. Preferably, the forward ends of brackets 148, 149, are disposed below the level of platform 106 thus tending to maintain the trough in contact with the guide rails.

Mounted for rolling movement on the side walls 134, 135, is the paint wiping and agitating carriage shown in detail in Fig. 16. This carriage comprises a pair of vertical side walls 150, 151, which are rigidly held by the cross braces 152-155. Rotatably mounted at the ends of braces 152, 153 are rollers 156, 157, which ride upon the corresponding members 134, 135. A similar set of rollers 158, 159 engage the under surface of the trough. Rotatably supported in the side walls is a shaft 160 which has fastened thereto by screws 161 the wiper blade or vane 3 of sufficient size with respect to the carriage so that it lightly wipes the bottom and side walls of the trough 2 as the carriage rides to the left and to the right (Fig. 1). Preferably, vane 3 is of Phosphor bronze or similar springy material which does not react or corrode when in contact with the paint. Vane 3 is arranged to assume two angular positions with respect to the trough. Thus when the carriage 107 is moved to the right (Figs. 1 and 3), the vane is inclined to form an angle opening to the right (Fig. 21). When it reaches the extreme left-hand position, it is automatically rotated so that during the reverse movement of the carriage, it is inclined in the opposite direction (Fig. 22). For this purpose, shaft 160 has attached thereto an arm 162, the upper end of which is V-shaped (see Fig. 1). Bearing against the inclined ends of arm 162 is a roller 163 rotatably mounted in a slot 164 in an arm 165 pivotally attached at 166 to an extension 167 of side wall 150. A coil spring 168 has one end attached to the wall 150 and the other to arm 165 thus maintaining roller 163 in engagement with an inclined edge of arm 162. The members 162, 163, form a modified form of toggle which can be "broken" in one position or the other by engagement between the roller 169 and the stops 170, 171, fastened to platform 106. Thus, assuming the vane is in the position shown in Fig. 16, and the carriage 107 is near its extreme right-hand position (Figs. 1 and 3) where the roller 169 engages stop 170, slight further movement of the carriage to the right rotates the arm 162 and shaft 160 in a clockwise direction (Fig. 16). The inclined end of arm 162 therefore rotates roller 163 and vane 3 in a counterclockwise direction in readiness

to execute its reverse wiping stroke (Fig. 22). Carriage 107 also carries adjacent the ends on one side a pair of rollers 172, 173, rotatable substantially at right angles to rollers 156. Preferably the rollers 172, 173, are mounted so that their axes can freely tilt towards each other a limited amount for purposes to be described. Thus as shown in Figs. 30 to 32, each roller is provided with a ball mounting 172a in a bi-part block 172b, 172c, attached by screws 172d to the wall 151. Consequently, each roller is capable of limited tilting movement with respect to a vertical axis.

The movement and alignment of carriage 107 is controlled by a trolley member 180 comprising two parallel plates 181, 182, rigidly held in spaced relation by three cross braces 183, 184, 185, which also serve as shafts for the respective guide rollers 186, 187, 188. The trolley rides on a rail 189 fastened to pedestals 190, 191, attached to platform 106. Attached to the lower side of the trolley at opposite ends are L-shaped brackets 192, 193, spaced apart a greater distance than the overall distance between the rollers 172, 173. The purpose of this is to insure that the carriage 107 is properly engaged by the trolley brackets 192, 193, should the carriage be slightly out of alignment with the trolley when the trough moves to its forward position. Because of the slight tilting movement of the rollers 172, 173, the carriage automatically aligns itself with the trolley. The trolley 10 is to assume its extreme left-hand position (Fig. 1) under control of spring 194 having one end attached to bracket 195 fastened to pedestal 190 and the other end attached to projection 196 on the trolley. The projection 196 is also connected to a belt or rope 197 passing around a small pulley 198, the opposite end of the belt being attached at 199 to a friction drum 200, journaled in the bearing plates 202, 203, which are held in rigid spaced relation by cross braces 204, 205, 206. Shaft 201 carries a toothed gear 207 which meshes with and is driven by a larger toothed gear 208 rotatable on its shaft 209 supported in plate 202. The gear 208 is driven under control of cam 121 (Figs. 1, 4 and 5). For this purpose, there is pivotally attached at 210 (Figs. 1 and 11) to plate 100, an arm 211 which carries a cam follower roller 212 which is engaged by cam 121. The upper end of arm 211 is pivotally connected to link 213 which is pivotally attached at 214 to gear 208. By this means the relatively small throw of cam 121 causes a greatly magnified rectilinear movement of the trolley 180 and thus of the carriage 107.

When the carriage has been moved to its extreme right-hand position, and then has been restored to its extreme left-hand position so as to subject the paint to a cycle of wiping and agitation in the trough 2, the trough together with the carriage is moved towards the rear of the machine where the recess 4 is in vertical alignment with the transfer and printing quills 5. For this purpose, there are attached to platform 106 (Figs. 2 and 3), a pair of plates 215, 216, which carry two sets of roller guides 217, 218, 219, 220, between which passes the horizontal arm 221. Arm 221 has at its rear end a block 222 which is arranged to engage the trough 2 to push it backward against the tension of the springs 146, 147. For this purpose, there is attached to plate 100 a bracket 223 in which is pivotally mounted an arm 224 carrying a cam 75

follower roller 225 to engage cam 130. Follower 225 is maintained in engagement with cam 130 by tension spring 226 connected between arm 224 and bracket 227 fastened to plate 100. Arm 224 has fastened to its upper end an L-shaped member 228 which engages roller 229 mounted in bracket 230 on member 221. A tension spring 230a contains the arm 228 in engagement with roller 229. When follower 225 is on the "low" part of cam 122 (Fig. 12), member 221 is in its forward position consequently the trough 2 is likewise in its forward position (Fig. 3) under control of springs 146, 147. After the carriage 107 has completed its forward and backward cycle of movement in the trough 2 to mix and agitate the paint in recess 4, cam 122 causes member 221 to move rearwardly thus forcing the trough to move rearwardly. While the trough is thus moving, the quill assembly unit 109 is gradually raised under control of cam 124 (Fig. 9) so as to provide sufficient clearance to allow the trough to move under the quills.

The quill printing unit

As shown more clearly in Figs. 1, 2, 9 and 10, the printing unit comprises a heavy hollow metal sleeve 109, which has fastened thereto a forwardly extending bracket 232 (Fig. 2). Fastened to bracket 232 is a platform 233 to the front edge of which is attached a similar but thicker platform 234. Fastened adjacent opposite ends of the platform 234 are two channel guides 235, 236 in which are adjustably movable blocks 237, 238, carrying at their forward ends rollers 239, 240. These rollers are arranged to ride upon corresponding vertical flat guides 241, 242, in the form of angle irons rigidly fastened at their lower ends to plate 100. Blocks 237 and 238 each have a threaded shank 243 threaded into a plate 244 carried by guides 235, 236, whereby the rollers can be adjusted horizontally against the guides 241, 242. Rigidly fastened to platform 234 in spaced relation therebelow is another similar plate 245, these plates being fastened together in spaced relation by screws 246 and sleeves 247 (Fig. 17). Likewise, fastened beneath plate 245 is the stripper plate 7 which is supported on guide members 249, 250, threaded into plate 245. Guides 249, 250, have compression springs 251, 252, located between the heads 253 of the guides and the other surface of plate 7. Normally therefore, plate 7 tends to approach plate 245 but are held in spaced relation by cams 254, 255 pivotally attached to the ends of plate 245 and adapted to engage rollers 256, 257, carried by the ends of plate 7. Each cam has an operating arm 258 whereby the plate 7 can be moved downwardly at the appropriate instant just the right amount so that its under surface is substantially flush at the extreme lower ends of the quills as illustrated in the magnified view of Fig. 20. If desired, the cams 254, 255, are adjustably fastened on the shafts 259 by set screws 260 whereby the amount of retraction of the quills 5 with respect to the plate 7 can be accurately regulated. Rigidly fastened to platform 234 are two pedestals 261, 262, across which is fastened by bolts 263, a plate 264. Likewise, supported in spaced relation above plate 264 by pedestals 265 is another plate 266. Each of the plates 7, 245, 234, 264, 266, is provided with a bank of perforations, the perforations and plates 264 and 266 being in vertical alignment, and the perforations in plates 7, 245, 234, also being in vertical

alignment. While there are the same number of perforations in all the plates, the perforations in plates 7, 245 and 234 are closer together than the perforations in plates 264, 266 although as a whole the perforations in the lower plates are directly beneath the perforations in the upper plates 264, 266. Rotatably mounted in the perforations in plates 264, 266, are a series of spindles 267, each of which has fastened to its upper end an individual toothed gear 268, all the gears being mutually in mesh as shown more clearly in Fig. 10 so that adjacent spindles rotate in opposite directions. These small gears are driven at a predetermined rate by means of a gear train 269, 270. Gear 270 is affixed to shaft 271 journaled in suitable bearings 272, 273, carried respectively by plates 266 and 264. Shaft 271 has affixed to its lower end a worm-wheel 274 driven by a worm 275 on shaft 276 journaled in bearing bracket 277. The rear end of shaft 276 (Fig. 2) carries a bevel gear 278 meshing with a similar bevel gear 279 whose shaft is journaled in bearing bracket 280. An extensible flexible shaft 281 connects gear 279 with gear 282 affixed to the shaft of motor 110.

Likewise, mounted for rotation in the corresponding openings in plates 7, 234 and 245 are the series of quills 5 shown in an enlarged cross section in Figs. 19 and 20. Each quill is connected to the corresponding spindle 267 by a flexible shaft 283 such as a fine steel wire or the like so that the quills rotate in unison with the spindles 267.

The weight of the quill assembly 109 is such that normally it is supported by cam 124 which engages roller 284 carried by the roller end of support sleeve 109. When the roller 284 is riding on the lowest part of cam 124, quills 5 are in printing contact with the web 9. After printing, cam 124 rests the quills to their maximum height thus allowing the trough 2 to pass underneath the quills as above described. While the trough is held stationary under the quills, the latter start to descend until roller 284 engages the low point 285 of the cam and the quills are lowered just sufficiently to allow their concave ends to be immersed in the paint in recess 4. Cam 124 then rests the quill sufficiently to clear the sides 134, 135 of the trough and thereupon cam 122 allows spring 226 to retract arm 229 whereupon springs 146, 147, restore the trough to its forward position where it is clear of the quills.

Just before the quills are lowered to their printing position, the web 9 is fed the desired amount to present the next area to be printed. For this purpose, the web is carried on a pay-off reel 286 supported for rotation on two spaced arms 287, 288, fastened to platform 106. Arms 287, 288, also carry a pair of guide rollers 289, 290 (Fig. 2), between which the web 9 passes. As shown in Fig. 29, the top of platform 106 in line with the reel 286 has fastened thereto a pair of guide rails 291, 292, between which the web passes. A plurality of spring fingers 293 are attached to the rails to hold the web flat against the platform. The left-hand end of platform 106 is provided with two slots 294, 295 adjacent the sides of the web guiding channel, and fastened to the platform in spaced relation thereto are a pair of slotted plates 296, 297, each having a slot of the same size and in alignment with the slots 294, 295. The web 9 is arranged to be gripped and fed by a plate 298 carrying at its forward end adjacent the edges, sets of pointed

teeth 10 which are arranged to be moved vertically to pierce the web, and thereafter they are moved bodily a predetermined distance to the left (Fig. 13) to feed the web the required distance. Thereupon member 298 is lowered to disengage the teeth 10 from the web and the feed device is returned to its initial position ready for the next feeding step. The piercing movement is controlled by cam 122 and the feeding movement is controlled by cam 123. Cam 122 engages roller 300, carried by arm 201 pivotally attached at 302 to plate 100. Arm 301 is pivotally connected through link 303 which in turn is pivotally attached to a lever arm 304 fastened to a shaft 305 mounted in bearing brackets 306, 307 (Figs. 13 and 29). Shaft 305 also has fastened thereto a lever arm 308 which has pivotally attached thereto an arm 309 pivotally connected to a bracket 310 carried by platform 311. Platform 311 is pivotally attached at 312 to a bracket 313 supported beneath platform 106. Consequently, as the high part of cam 122 engages roller 300, the left-hand end of platform 311 is raised around the pivot 312 and forces the left-hand end of member 298 with its teeth 10 in a substantial vertical direction a sufficient distance to cause the teeth 10 to pierce the web 9. Thereupon, the high part of cam 123 engages a roller 314 carried by the arm 315 pivotally attached at 316 to plate 100. Arm 315 is likewise pivotally attached at 317 to the member 298 whose roller 318 rests on the platform 311. Consequently, when the high part of cam 123 engages the roller 314, the member 298 is moved to the left against the force of tension spring 319, thus feeding the web 9 the predetermined distance.

For the purpose of removing the excess paint which projects below the stripper plate 7 as above described, there is provided a horizontally movable wiper blade 8 (Figs. 17, 18 and 34), which is supported by two arms 325, each attached to corresponding rollers 326, mounting for rolling movement in corresponding longitudinal grooves 327 in the front and rear vertical sides of plate 7. A spring 328 normally holds the rollers and blade 8 adjacent one end of plate 7. Arms 326 are connected by cord 329 passing over a pulley 330 and thence to the upper end 50 of lever 331 pivoted at 332. The normal position of lever 331 is indicated in dotted outline in Fig. 34 where it engages stop member 333. Attached to cam shaft 118 (Figs. 4 and 34) is an arm 334 which at the right instant when the 55 ends of the quills are substantially flush with stripper plate 7 (Figs. 20 and 25), engages short arm 335 of lever 331 and rotates the latter clockwise, thus pulling the wiper blade rapidly to the left whereby it strips off the excess paint which protrudes below the stripper plate 7.

Referring to Fig. 35 there is shown in magnified form a portion of the printed web 9 wherein the indicia has been printed as described. As will be seen the indicia is formed in a series of 65 discrete raised dots 336 each of spherical sector shape corresponding to the shape of the depressions in the quill ends. Because of the fact that the quills are rotating while the paint is being deposited on web 9, each dot has a sharp outline and if desired a greater or less spacing may be provided between succeeding dots. Notwithstanding that the dots are spaced, when the indicia is viewed in the dark, it appears to be a continuous strip of light. This enables a considerable saving in the quantity of radium

luminous material necessary to form the luminous indicia. It will be understood of course that in printing such devices as clock dials and the like with a plurality of separate indicia, that the quills will be arranged in groups, each group corresponding to its respective indicia to be printed and merely for simplicity of the drawings, the machine is shown as printing a single indicia. In order to reduce the load on the driving motor during the raising of the quill-stripper assembly or cam 124, the assembly is partially supported by two bowed leaf springs 337, 338 (Fig. 15) which have their lower ends fastened to the plate 100 and their upper ends fastened to a bracket 339 (Fig. 2) carried by the sleeve 231. The springs 337 and 338 tend to push the quill-stripper assembly upwardly but the weights of the latter is sufficient to maintain roller 284 in engagement with the cam 124 so that when the cam rotates to raise the assembly, it is assisted by the springs 337 and 338. Preferably the rear pedestal 108 is joined to the pedestals 190, 191, by rigid inclined brace members 340, 341.

If it is desired to print the raised characters each in a continuous strip or rib as distinguished from a series of dots, an arrangement such as shown in Figs. 35 and 36 can be employed. In this embodiment, the quills 5 pass through a perforated die member 345, the lower end 346 of which is chamfered to a sharp edge 347 and forms a continuous groove or channel bounding the quills 5. The die is slidable in the stripper plate 7 and is supported from the upper plate 245. For this purpose, die 345 carries a plurality of radially extending pins 348 which register with inclined slots 349 in a ring 350. Ring 350 has an outwardly extending horizontal flange which rides on a corresponding inwardly extending horizontal flange on ring 351 fastened by screws 352 to plate 245. Fastened to ring 350 is an operating arm 355 which is adapted to be engaged by member 354 which is operated either from the main cam shaft 118 or if desired a fixed abutment may be provided on the platform 106 so that during the downward movement of the quill-stripper assembly as above described, and just before the quills are about to assume their printing position, the said abutment engages the arm 353 to rotate to ring 350 whereby the die 345 is moved downwardly so that the edge 347 engages the printing web. Since the die 345 is carried by the member 245, it normally projects below the surface of the stripper plate 7. However, during the downward movement of the quill-stripper unit, the engagement of the arm 353 with member 354 raises the die 345 so that the lower ends of the quills project below the under face of member 7 and these ends can dip into the paint trough for loading as above described. After the quills have been loaded, the member 7 is moved downwardly to the dot-dash line position as already described so that its under face is in substantially the same plane with the ends of the quills. Consequently, the wiper blade 8 can then move across the quill ends to strip off the excess paint as above described and during this downward movement the member 345 also strips the excess paint off the peripheral end of the quills as hereinabove described. After the quills have been stripped the unit is lowered to printing position as already described so that the edge 347 engages the printing web and the paint is discharged from the lower ends of the quills on to the printing

surface. During this discharge, the quills are constantly rotating as already described and the paint which is discharged is confined to the outline of the character as determined by the shape 5 of the groove or channel in the lower end 346 of the die. By this arrangement therefore, the paint is deposited in a continuous raised rib, the boundaries of which are sharply delineated by the edge 347.

10. What I claim is:

1. The method of printing which comprises immersing a plurality of hollow-ended quills in the printing medium, rotating the quills around their individual longitudinal axes while immersed, and transferring the printing medium from the quills to a receiving surface while maintaining the quills rotating.
2. The method according to claim 1 in which adjacent quills are rotated in opposite directions.
3. The method of printing which comprises immersing the hollow ends of a plurality of printing quills in a printing medium, rotating the quills around their individual longitudinal axes to cause the hollow ends to pick up a quantity of the medium, bringing the loaded quills into printing relation with a receiving surface, and rotating the quills to deposit the printing medium thereon.
4. The method of printing employing a plurality of hollow-ended printing quills arranged in banks having a conformation corresponding to indicia to be printed, which comprises rotating the quills around their individual longitudinal axes while immersing their hollow ends in a viscous printing medium, withdrawing the quills, stripping excess medium from the quill ends, moving the quills into printing relation with a receiving surface, and rotating the quills 30 while in such printing relation.
5. The method of printing employing a printing medium of a liquid suspension of heavy particles such as radium-luminous particles which tend to separate out, which method comprises applying the medium to the ends of a bank of printing quills while maintaining the quills in rotation about their individual longitudinal axes, transferring said medium from said quills to a receiving surface, and maintaining the medium in constant agitation from the initial loading of the quills to the final printing on said surface.
6. The method according to claim 5 in which the medium is loaded on to the quills and is transferred therefrom to the printing surface with a minimum of pressure on the said particles.
7. The method of transferring radium-luminous paint and the like from a supply receptacle to a printing surface employing a bank of concave-ended quills which comprises, loading the quills by immersing and rotating them around their individual longitudinal axes in the paint, and transferring the paint from the quills by rotating the quills with the peripheral surface of the paint on the quills in light contact with said surface.
8. The method of printing raised indicia with radium-luminous paint and the like employing concave-ended quills, which comprises arranging the quills in banks conforming in cross-sectional trace to the indicia to be printed, loading the said concave ends with paint, and rotating the loaded ends around their individual longitudinal axes and in close proximity to the re-

ceiving surface to form the indicia with a series of discrete raised dots of said paint.

9. The method according to claim 8 in which the ends of the quills are located all in the same plane, and the loaded ends thereof are stripped of excess paint prior to transfer to said receiving surface.

10. A surface printing device comprising a bank of printing fingers each having a solid concave end to receive a quantity of printing medium, said fingers being arrayed so that their cross-sectional trace conforms to the shape of the indicia to be printed, and means to maintain said fingers in rotation about their individual longitudinal axes during printing.

11. A printing device according to claim 10 in which said fingers are mounted so as to be moved as a unit into and out of printing relation with a receiving surface.

12. A surface printing device comprising a bank of solid but concave-ended quills each arranged to receive a quantity of printing medium only in the cavity at the end thereof, and means to maintain each quill in rotation about its axis while it is being loaded with printing medium and while it is in printing relation with a receiving surface.

13. A surface printing device according to claim 10 in which the ends of said fingers are of metal having a minimum of adhesive force with respect to the printing medium, the dimensions of the concave end being correlated with the viscosity of the printing medium so that the latter is retained therein mainly by surface tension.

14. A printing device according to claim 10 in which the ends of said fingers are of stainless steel alloy.

15. A printing device according to claim 10 in which the ends of said fingers are of an alloy 40 of the non-magnetic stainless steel type.

16. A surface printing device according to claim 10 in which all said fingers are individually rotatable about their respective longitudinal axes and are connected to a common driving shaft whereby they are maintained in rotation around their individual longitudinal axes during loading and printing.

17. In a surface printing device of the character described, a frame, a plurality of concave-ended printing fingers carried by said frame, means to maintain each finger individually rotating about its longitudinal axis, and means to move said frame whereby said fingers can be brought into and out of printing relation with a receiving surface while they are rotating.

18. A surface printing device according to claim 17 in which said frame carries upper and lower horizontal perforated plates, and a plurality of driving spindles are mounted for rotation in the upper plate, each spindle being connected by an individual flexible shaft to a corresponding one of said fingers.

19. A surface printing device comprising a bank of vertically mounted rotatable spindles arrayed to conform in cross-sectional trace to the shape of indicia to be printed but with the trace larger than the indicia, a bank of vertically mounted hollow-ended printing quills arrayed to conform in cross-sectional trace to the shape of the indicia but with a trace smaller than the first-mentioned trace, and an individual flexible shaft connecting each spindle to a corresponding quill.

20. A printing device according to claim 19 in 75

which each spindle carries a toothed gear and with adjacent gears in mesh, all said gears being driven from a common drive whereby adjacent quills are rotated in opposite directions.

5 21. In a machine of the character described, a vertically movable printing quill unit having a plurality of solid but concave-ended printing quills, a longitudinally movable paint trough unit, a reciprocating wiper blade unit for said trough, a wiper unit for said quills for stripping excess paint from the ends of said quills prior to printing, a single source of motive power for said units, and timing means for controlling the movement of said units in the following sequence; reciprocating said wiper blade to agitate the paint in the trough, raising the quill unit, reciprocating the quill wiper unit, moving the trough underneath the quill unit, lowering the quill unit to immerse the quill ends in the trough, raising the quill unit to clear the trough, withdrawing the trough from beneath the quills, and then lowering the loaded quills into printing position.

15 22. In a machine of the character described, a vertically movable frame, a plurality of hollow-ended printing quills carried by said frame each rotatable for loading and discharging printing medium, a stripper plate carried by said frame and vertically movable with respect to the quill ends, means to move the plate so that its lower face is substantially flush with the lower ends of said quills, a wiper blade with its wiping edge in contact with the under face of said plate, and means to reciprocate said blade after said quills have been loaded and while the lower surface of said plate is substantially flush with the quill ends.

30 23. In a surface printing machine of the character described, a plurality of rotatable printing quills arrayed to conform in cross-sectional trace to the shape of the indicia to be printed, means to maintain said quills in continuous rotation during printing, a member bounding the lower ends of said quills comprising means through which the quills pass, the lower end of said member having a channel of the shape of the indicia, cooperating with the quills to define the boundaries of the printed indicia.

45 24. In a machine of the character described, a plurality of rotatable printing quills, a perforated plate through which the lower ends of the quills project for printing, said quills being arrayed to conform in cross-sectional trace to the shape of the indicia to be printed, a member bounding the said quills and slidably mounted in said plate with respect to said quills, means to move said plate so that in one position its under face is substantially flush with the ends of the quills and in another position the quill ends project beneath said under face, and means effective when said quills are about to assume a printing position to move said bounding member into contact with the printing surface.

50 25. A machine according to claim 24 in which said bounding member is in the form of a perforated die slidably mounted in said plate, said die when the quills are in printing position being moved so that its lower bounding edge is substantially flush with the lower ends of the printing quills.

65 26. A printing die comprising a perforated solid member having a series of perforations arrayed to conform in cross-sectional trace to the shape of the character to be printed, the lower face of said die being formed with a bounding channel, and a plurality of printing quills passing through

the perforations in said die and having their printing ends arranged to be substantially flush with the edge of said channel when in printing position, said quills having means to maintain them rotating about their individual longitudinal axes during printing.

27. In a surface printing machine, a printing web guiding means, a plurality of rotatable solid but concave-ended printing fingers mounted for vertical movement with respect to said web, means to rotate each quill around its individual longitudinal axis, means to load the concave ends of said fingers with printing medium, means to

move said fingers into printing relation with said web while the latter is stationary, a stripper plate adjustably mounted with respect to the ends of said printing fingers, means to move the stripper plate longitudinally of the said fingers to strip excess paint from the concave ends of the fingers and to determine the quantity of printing medium protruding below said stripper plate, and a stripper blade movable across said stripper plate to strip off the said protruding medium.

MARVIN R. SAXBY.
